UNITED STATES PATENT OFFICE.

FRANK P. GRZYBALA, OF THOMPSONVILLE, CONNECTICUT.

PARACHUTE OR GLIDER.

Application filed March 17, 1926. Serial No. 95,266.

This invention relates to certain new and useful improvements in parachutes or gliders in the form of a pair of plane or wing members, one arranged at each side 5 of the body of a person for detachable connection with the outer sides of the arms adjacent to the shoulders and intended for manual manipulation similar to the wings of a bird.

10 A further object of the invention is to provide a parachute or glider of the type above set forth wherein the wing or plane at each side of the body is formed of hinged sections with a strap and hand clamping device carried by the section for attachment 15 to the upper arm and hand of a person, spring hinges connecting the sections of each plane with the sections retained in an open operative position by the hand clamp, 20 the latter being manually operable for releasing the outer section of the plane or wing to permit automatic collapsing or folding movement thereof when desired.

With the above and other objects in view 25 that will become apparent as the nature of the invention is better understood, the same consists of the novel form, combination and arrangement of parts hereinafter more fully described, shown in the accompanying drawings and claimed.

In the drawings, wherein like reference characters designate corresponding parts throughout the several views,

Figure 1 is a top plan view of the 35 parachute or glider constructed in accordance with the present invention, the side planes or wings being operatively positioned upon a person and attached to the body and arms,

Figure 2 shows bottom plan views of the 40 two side wings or planes,

Figure 3 is an edge elevational view of one of the planes in its folded position, and

Figure 4 is a fragmentary bottom plan view showing the manually operable hand gripping device in its released position to 45 permit folding of the wing sections.

The parachute or glider comprises a pair of side wings or planes of identical construction and each wing is formed of a pair 50 of sections 1 and 2 hinged together at their longitudinal meeting edges by spring hinges 3 that normally cause the wing sections 1 and 2 to assume a folded or collapsed position as shown in Fig. 3 with the 55 sections superposed and so retained by the

spring clips 4 carried by the forward ends of the wing section 2 engaging the adjacent edge of the wing section 1 as shown. The wings are formed of any suitable material, such as aluminum or the like and the 60 forward ends thereof comprised of continuous sheets while the rear tail ends of the wings are constructed in simulation of bird feathers and comprise strips 5 connected together by brace bars 6 and 7 carried by 65 each of the sections 1 and 2, the brace bars 7 being hinged together as at 8 at their meeting ends as shown in Figs. 1 and 3.

The wings being attached to the outer 70 sides of the arms of a person as shown in Fig. 1, each intersection 1 carries a pair of cooperating straps 9 upon the lower face thereof for encircling the arm 10 illustrated by dotted lines in Fig. 1, the inner edges of each section 1 having a cutout portion 75 11 to intimately contact the arm. A breast and back strap 12 and 13 respectively carried by the wing sections 1 at opposite sides of the cutaway portion 11 engage the person as shown in Fig. 1 to support the parachute 80 in position. With the side wings or planes in position upon a person as shown in Fig. 1 and it being desirable to hold the outer sections 2 of the wings in their extended 85 operative positions above the arms and hands of the person and against tension of the spring hinges 3, devices are carried by the lower face of each outer section 2 for releasably clamping the hand of the person and to be so retained by the out- 90 stretched arms.

The hand gripping devices are shown 95 more clearly in Figs. 2, 3 and 4, the curved hand engaging straps 14 being hingedly supported at one end at 15 to the bracket 16 carried by the outer wing section 2, the other 100 free end of the clamping strap 14 carrying a finger grip 17 that is engaged by the tensioned keeper 18 to retain the clamping strap 14 in its closed and locked position shown in Figs. 2 and 3. The coil spring 19 attached at one end at 20 to the wing section 2 has its outer end secured as at 21 to the clamping strap 14 adjacent its hinge mounting 15, the spring 19 being positioned 105 for either holding the clamping strap 14 in its closed position and when said clamping strap is moved to an open position rearwardly of the hinge mounting 15, the 110 spring also tends to retain the clamping

strap in an open position as shown in Fig. 4. The devices for releasing the clamping strap 14 include a bell crank lever 22 pivotally mounted as at 23 upon the wing section 2 with one leg 24 thereof having a link connection 25 with the clamping strap 14 while an operating link 26 for the bell crank lever 22 is attached to the outer end of the other leg thereof and is slideable thru a guide 27 with the terminal end 28 thereof positioned in proximity to the fingers of the hand clamped by the straps 14. The coil spring 29 attached at one end to the offset portion 30 of the sliding link 26 with the other end thereof attached as at 31 to the wing section 2 normally holds the free end of the leg 24 of the bell crank in its forward direction toward the clamping strap 14.

The manner of wearing the parachute or glider is clearly illustrated in Fig. 1, the side wings or planes being disposed outwardly of and above the arms 10 of a person and mounted in position by the arm straps 9 and the chest and back straps 12 and 13. The clamping straps 14 engaging the hand of the person as illustrated by dotted lines in Fig. 1 retains the outer wing sections 2 in their extended operative positions during flight. When it is desired to release the outer wing sections 2 to be folded upon the inner wing sections 1 and for removing the parachute from the body, the operating rod or link 26 at the forward end thereof is engaged by the fingers of the person for shifting the same against the tension of the spring 29 to move the bell crank lever 22 and thru the medium of the link connection 25 between the bell crank lever and clamping strap 14 release the latter from the retaining clip 18 to the position shown in Fig. 4 and at which time the spring 19 will retain the clamping strap in its open position while the spring hinges 23 will automatically shift the outer wing sections 2 into the folded position shown in Fig. 3. The side wings may be manipulated during flight in simulation of the wings of a bird and the general outline of each wing or plane being similar to a bird's wing, sustained flight is easily attainable.

While there is herein shown and described the preferred embodiment of the present invention, it is, nevertheless to be understood that minor changes may be made therein without departing from the spirit and scope of the invention as claimed.

What is claimed is:—

1. In a device of the character described, a pair of wings adapted for attachment to the arms and body of a person, each wing being formed of sections connected by spring hinges and normally assuming superposed positions and means carried by the outer hinged section for gripping the hand of a person for holding the two sec-

tions alined in operative positions and being releasable by the hand to be automatically shifted to inoperative position.

2. In a device of the character described, a pair of wings adapted for attachment to the arms and body of a person upwardly and outwardly of the arms, each wing comprising a pair of sections, spring hinges connecting the sections and causing them normally to assume superposed positions, a tensioned hinged strap on the outer section for gripping the hand of a person to retain the two sections in alined operative positions, a keeper for the strap, and manually operable releasable means for the strap to permit the spring hinges to collapse the sections.

3. In a device of the character described, a pair of wings adapted for attachment to the arms and body of a person upwardly and outwardly of the arms, each wing comprising a pair of sections, spring hinges connecting the sections and causing them normally to assume superposed positions, a tensioned hinged strap on the outer section for gripping the hand of a person to retain the two sections in alined operative positions, a keeper for the strap, a bell crank lever pivoted on the section, a link connection between one leg of the bell crank and the strap, and a manually operable link rod attached to the other leg of the bell crank for releasing the strap to permit the spring hinges to collapse the sections.

4. In a device of the character described, a pair of wings adapted for attachment to the arms and body of a person upwardly and outwardly of the arms, each wing comprising a pair of sections, spring hinges connecting the sections and causing them normally to assume superposed positions, a tensioned hinged strap on the outer section for gripping the hand of a person to retain the two sections in alined operative positions, a keeper for the strap, a bell crank lever pivoted on the section, a link connection between one leg of the bell crank and the strap, and a manually operable link rod attached to the other leg of the bell crank for releasing the strap to permit the spring hinges to collapse the sections.

5. In a device of the character described, a pair of wings adapted for attachment to the arms and body of a person upwardly and outwardly of the arms, each wing comprising a pair of sections, spring hinges connecting the sections and causing them normally to assume superposed positions, a tensioned hinged strap on the outer section for gripping the hand of a person to retain the two sections in alined operative positions, a keeper for the strap, a bell crank lever pivoted on the section, a link connection between one leg of the bell crank and

- the strap, a manually operable link rod attached to the other leg of the bell crank for releasing the strap to permit the spring hinges to collapse the sections, a spring associated with the strap for holding the same in either open or closed positions, and a spring associated with the operating means for the strap for holding the operative means in set position.

6. In a device of the character described, a pair of wings adapted for attachment to the arms and body of a person upwardly and outwardly of the arms, each wing comprising a pair of sections, spring hinges connecting the sections and causing them normally to assume superposed positions, a tensioned hinged strap on the outer section for gripping the hand of a person to retain the two sections in alined operative positions, a keeper for the strap, a bell crank lever pivoted on the section, a link connection between one leg of the bell crank and the strap, and a manually operable link rod attached to the other leg of the bell crank for releasing the strap to permit the spring hinges to collapse the sections, each section comprising a thin continuous sheet at its forward end and connected strips for the rear tail portions of the sections, cross braces for the wing section strips and pairs of said cross braces being hinged together at their meeting ends.

7. In a device of the character described, a pair of wings adapted for attachment to the arms and body of a person upwardly and outwardly of the arms, each wing comprising a pair of sections, spring hinges connecting the sections and causing them normally to assume superposed positions, a tensioned hinged strap on the outer section for gripping the hand of a person to retain the two sections in alined operative positions, a keeper for the strap, manually operable releasable means for the strap to permit the spring hinges to collapse the sections, a spring associated with the strap for holding the same in either open or closed positions, a spring associated with the operating means for the strap for holding the operative means in set position, each section comprising a thin continuous sheet at its forward end and connected strips for the rear tail portions of the sections, cross braces for the wing section strips and pairs of said cross braces being hinged together at their meeting ends.

8. In a device of the character described, a pair of wings adapted for attachment to the arms and body of a person upwardly and outwardly of the arms, each wing comprising a pair of sections, spring hinges connecting the sections and causing them normally to assume superposed positions, a tensioned hinge strap on the outer section for gripping the hand of a person to retain the two sections in alined operative positions, a keeper for the strap, a bell crank lever pivoted on the section, a link connection between one leg of the bell crank and the strap, a manually operable link rod attached to the other leg of the bell crank for releasing the strap to permit the spring hinges to collapse the sections, each section comprising a thin continuous sheet at its forward end and connected strips for the rear tail portions of the sections, cross braces for the wing section strips and pairs of said cross braces being hinged together at their meeting ends.

In testimony whereof I affix my signature.

FRANK P. GRZYBALA.
